UNITED STATES PATENT OFFICE.

DANIEL E. KEMPSTER, OF BOSTON, MASSACHUSETTS.

SPRING-BALANCE SHADE-ROLLER.

SPECIFICATION forming part of Letters Patent No. 251,893, dated January 3, 1882.

Application filed September 5, 1881. (No model.)

To all whom it may concern:

Be it known that I, DANIEL E. KEMPSTER, a citizen of the United States, residing at Boston, in the county of Suffolk and State of Massachusetts, have invented certain new and useful Improvements in Spring-Balance Shade-Rollers; and I do hereby declare that the same are fully described in the following specification and illustrated in the accompanying drawings.

Figure 1 is an elevation, partly in section, constructed with my improvements; Fig. 2, a transverse vertical section of the same on the line V V, shown in Fig. 1, showing the position of the locking device when the roller is in operation in its brackets; Fig. 3, a similar view, showing the roller as removed from its brackets and the spring locked. Figs. 4 and 5 are respectively perspective details of spindle-cam and spring locking cylinder. Fig. 6 is a transverse vertical section, on the line W W shown in Fig. 1, of the roller-journal and the inner side elevation of its friction-bracket. Fig. 7 is a top edge view of the shade-stick; Fig. 8, a side elevation thereof, and Fig. 9 a cross-section on the line y y of Fig. 8.

My invention has relation to that class of spring-rollers which are adapted for use with weighted shades, the spring serving to wind up the shade on the roller when such shade is raised and relieved of its weight, the latter serving to counterbalance the spring when the shade is at a state of rest.

Referring to the accompanying drawings, A indicates a shade-roller having a hard-wood cap, A', and a spindle, B, with angular end b, which rests in bracket C, the opposite end of said roller having a journal, a, which rests in bracket D, having a friction-bearing, d.

E is a spiral spring, whose opposite ends are secured to the roller and spindle, respectively.

F is a shade, secured to the roller in the usual manner, and G is a weighted slat attached thereto.

H is a cam with corrugations 1 2 3, &c., and circular sides h h', and having a pocket, e, said cam being fast on the spindle B.

I is the corrugated locking-cylinder.

G is the grooved shade-stick for the reception of the weight K.

There are in this invention several distinct

features of improvement, which I will describe in succession.

My first improvement consists in the employment of a fabric or material composed of cotton and rubber, for the bearings or journals of the rollers, whereby very valuable results are effected. First, the peculiar friction produced is especially adapted to balance-spring fixtures wherein it is difficult or impossible to so adjust the length and strength of the spring to the varying sizes and weights of shades that it will balance the same equally at the top and bottom of the window, balance-shades being apt to run up at the bottom and run down at the top of the window; but the friction of this material as a bearing or journal is such that the spring may be adjusted to sufficient strength at the top to hold the shade close up, and yet not be so strong as to overcome the friction when the shade is lowered to the bottom of the window; second, the material is such that it will wear an indefinite length of time and will never produce the slightest creaking—an objection so prevalent and annoying with journals or bearings of shade-rollers. As is shown in Figs. 1 and 6, I prefer to use this material in the form of a ring or bushing, d, secured inside the bracket-head, and a journal of wood, a, on the end of the roller A, running loosely therein. In cutting out these rings the rubber cuts close and smooth; but the cotton, owing to its fibrous nature, cuts so as to project more or less above the surface of the rubber, and therefore peculiarly adapts itself, to a large extent, as a releasing friction-bearing, for when the shade, with its weighted slat or tassel, causes the journal to press down hard upon the bearing the fibrous material yields, and the rubber, acting on the journal, causes great friction, and is capable of sustaining the weight of the heaviest shades, thus admitting of using a much lighter spring than could ordinarily be used. Also, as the shade and its weighted slat or tassel are raised by the hand the tendency of the spring is to slightly lift the journal a within the friction-ring d, and thus release a greater part of the friction aforesaid. The shade may be raised to any desired height, even thrown up so the bottom of the shade will come completely up to the roller, so freely does the journal revolve on the fibrous

material or cotton when the weight is removed and the shade ascending. This is obviously a great advantage, as all will see who have ever tried to raise a balance-shade to the top of a high or even ordinary window while standing only on the floor. Another thing which commends this material for this purpose is its cheapness compared with felt, leather, or any mechanical devices used for producing friction.

10 The fabric is preferably made of sheets of cotton duck, of suitable weight, cemented together with rubber or gum, similar to ordinary rubber belting. This fabric I also use as a friction-disk on the side of the spool on common 15 cord-rollers, and it has the necessary friction to sustain the weights of the heaviest shades.

Another feature of my invention consists in the arrangement of the automatic locking device, and its combination with a friction device 20 and a weighted slat or tassel in a spring-balance roller, as referred to in lines 70 to 75 on page 2 of the specification forming part of United States Patent No. 224,596, application filed July 15, 1878, and granted to me February 17, 1880.

25 Therein the cam is made double, and, with two locking-cylinders, is arranged as an automatic lock, and said patent sets forth and broadly claims the combination, with a spring shade-roller, of a cam fixed to the spindle, a locking- 30 roller, and an annular flange; also a cam fixed to the spindle, and provided with a pocket, *e*, for holding the locking roll or cylinder out of engagement, and hence I do not claim them now.

In the present case I use a single cam, *H*, and 35 locking-cylinder, *I*, as a spindle-lock for locking the spring on removal of the roller from its brackets. A lip, *b*, on the side of the angular end *b* of spindle *B* fits into a corresponding notch in bracket *C*, and thus insures the 40 cam being always on the top, so as when the roller is operating in its brackets the locking-cylinder *I* is held in the pocket *e* out of engagement, as shown in Figs. 1 and 2. On the removal of the roller from its brackets the 45 cam *H* throws the locking-cylinder *I* out of the pocket *e* and into engagement with the annular flange *A'*, thus wedging and securely locking the spring and preventing its unwinding, as shown in Fig. 3. The cap *A'*, which 50 forms the annular flange for locking-cylinder *I* to engage with, I make of a stronger and harder wood than the main body of the roller, so as to withstand the abrasion consequent upon locking. It is also neater in appearance, 55 cheaper to manufacture, and more noiseless than a metallic end. I form corrugations 1 2 3 4, &c., on the surface of the cam *H*. Also the locking-cylinder *I* is slightly corrugated. This produces a more sure and positive lock 60 than when the cylinder is smooth or polygo-

nal. The circular sides *h h'* of the cam *H* are for the purpose of protecting the locking-cylinder *I* and preventing the frictional contact of the inner face of the cap *A'* from throwing the locking-cylinder *I* into engagement with the cam *H* and flange or cap *A'* under a rapid upward movement of the shade.

Another feature of my invention is the improved shade-stick and weight, constructed as shown in Figs. 7, 8, and 9. The stick *G* is 70 grooved on both sides, and also one edge. This grooving is accomplished cheaply by sawing, the sticks being dropped edgewise on saws of suitable diameters placed together, and are fed along a sufficient distance for the length of 75 groove required for the weight *K* when they are raised from contact therewith. The weight *K*, when placed in the groove *g*, does not project beyond the stick *G*, but merely comes out flush therewith. They may be constructed very 80 cheaply of cast-iron, same grade as ordinary window-weights, and any holes for the reception of screws, &c., may be cast in them. I prefer to use the form shown in Figs. 8, 9, and 11, as the weight so constructed is heavy enough 85 when made very short, thus admitting of cutting off the stick short. It also, when placed on the stick, attaches itself securely thereto by clamping the central part of the grooved portion of the stick between its sides, thus dispensing with the necessity of any screws or tacks for holding it in place.

What I claim as my invention is—

1. A journal or bearing for curtain or shade rollers, having a bearing-surface of cotton and rubber, substantially as and for the purpose herein specified.

2. The spindle-cam *H*, having sides *h h'* and corrugations 1 2 3 4, &c., and pocket *e*, for the purpose set forth.

3. The locking-cylinder *I*, corrugated on its periphery, adapted to secure frictional contact, as represented and set forth.

4. The shade-stick *G*, grooved on its edge and both of its sides to receive and hold the weight *K*, substantially as shown in Figs. 7, 8, and 9.

5. A metal weight for loading window-shade sticks constructed as described, so as to clasp or clamp a portion of said stick and attach itself thereto without the necessity of any other fastening, substantially as shown in Figs. 7, 8, and 9.

In testimony whereof I have affixed my signature in presence of two witnesses.

DANIEL E. KEMPSTER.
